UNITED STATES PATENT OFFICE.

CORNELIA A. HOPKINS, OF NEW YORK, N. Y.

SUPPORTING DEVICE.

No. 878,801.

Specification of Letters Patent.

Patented Feb. 11, 1908.

Application filed December 7, 1900. Serial No. 39,002.

To all whom it may concern:

Be it known that I, CORNELIA A. HOPKINS, a citizen of the United States, residing at New York city, county of New York, and 5 State of New York, have invented certain new and useful Improvements in Supporting Devices, fully described and represented in the following specification and the accompanying drawings, forming a part of the 10 same.

This invention relates to an improved fastening or supporting device which shall be especially adapted for use in supporting or securing together parts of garments, but may 15 also be used for supporting or securing other articles such as curtains and all kinds of drapery.

The invention aims especially to provide a device of this kind in the use of which all 20 necessity of sewing or previous preparation of the article on which it is used is avoided.

As a full understanding of the invention can best be given by a detailed description of a preferred form of fastening device constructed to embody the invention and preferred modifications thereof, such a description will now be given in connection with the 25 accompanying drawings, in which—

Figure 1 is a view showing one manner of 30 using my improved fastening device for securing a woman's skirt. Figs. 2 and 3 show the two members of the preferred form of fastening device separated from each other. Fig. 4 is a sectional view showing the two 35 members of the fastening device shown in Figs. 2 and 3 secured together. Figs. 5 and 6 are views similar to Figs. 2 and 3 showing a modified form of fastening for securing the two parts together. Fig. 7 is an edge view of 40 the part shown in Fig. 6. Figs. 8 and 9 are views similar to Figs. 2 and 3 showing still another form of fastening for securing the two parts together, and Fig. 10 is a cross-sectional view of the two parts shown in Figs. 8 45 and 9 secured together.

Referring to the drawings, and first to Figs. 2, 3 and 4, the fastening device comprises two plates A and B each of which is provided with a double pin 2 formed preferably of a single length of wire bent to the proper form and pivotally connected to one end of the plate, the end of the plate being for this purpose bent to form an eye 3. The opposite end of each plate is provided with 50 keepers 4, formed preferably by bending lateral extensions of the plate first inward

and then outward as shown best in Fig. 10. The outward extending portion *a* of the keepers thus form guides which by deflecting the points of the pins inward as they are 60 swung into place materially aid in bringing the points of the pins into position beneath the keepers. The plates are preferably cut away at either edge near the ends having the keepers, as shown, for convenience in manipulating the pins.

Each of the plates A and B is provided with one member of a device by which the plates are separably secured together. In the preferred form shown in Figs. 2, 3 and 4, 70 this device consists of a ball and socket fastening, the ball or knob 5 being on one plate, as A, and the socket or opening 6 being in the other plate, B. The two members of the device for securing the plates together 75 are preferably positioned near the ends of the plates as shown, thereby facilitating the operation of securing the two plates together. The pins and keepers are preferably arranged oppositely on the two plates, that is, so that 80 when the plates are secured together, the pins of one plate will extend in the direction opposite to that in which the pins of the other plate extend. This is a feature of importance, since the endwise strain of the 85 garment or other article on each of the parts of the fastening device will thus be in the same direction relatively to the pins.

In the form of the device shown in Figs. 5, 6 and 7, instead of the ball and socket fastening for securing the parts together, a knob and slot fastening is provided, the knob 10 being carried by one plate and a suitably shaped slot 11 formed in the other plate. As here shown, also, one of the plates, as B, 95 is provided with a hook 12 intended for engaging the upper edge of a belt when the device is used on the band of a skirt.

In the construction shown in Figs. 8, 9 and 10, the plates are provided with a sliding 100 catching device formed by striking up portions of the bodies of the plates to form opposed and oppositely turned over edges 15 and 16 respectively for engaging each other for holding the plates together, as shown in 105 Fig. 10.

It will be understood that other suitable devices may be employed for securing the two parts of my improved fastening or supporting device together.

What I claim is:

1. A supporting or fastening device com-

prising two plates A and B each formed at one end with an eye 3 and at the other end with keepers 4 having outwardly flaring guides *a* and having a double pin 2 pivoted in the eye 3, and each of said plates being provided with a member of a device for securing the plates together, substantially as described.

2. A supporting or fastening device comprising two separable parts each provided with double pins and keepers having outwardly flaring guides *a*, and each provided with a member of a device for securing the parts together, substantially as described.

15 3. A supporting or fastening device comprising two plates A, B each formed at one end with an eye 3 and at the other end with keepers 4 having outwardly flaring guides *a*, and having a double pin 2 pivoted in the eye 3, and each of said plates being provided

with a member of a device for securing the plates together, and one of said plates having a hook 12, substantially as described.

4. A supporting or fastening device comprising two plates A and B each formed at one end with an eye 3 and having at the other end tongues bent first inward to form keepers 4 and then outward to form outwardly flaring guides *a*, and having a double pin 2 pivoted in the eye 3, and each of said plates being provided with a member of a device for securing the plates together, substantially as described.

In testimony whereof, I have hereunto set my hand, in the presence of two subscribing witnesses.

CORNELIA A. HOPKINS.
